United States Patent Office.

FREDERICK WHITEHOUSE, OF BROOKLYN, NEW YORK, ASSIGNOR TO THE WHITING MANUFACTURING COMPANY, OF NEW YORK CITY.

Design No. 3,391, dated February 23, 1869.

DESIGN FOR A SPOON.

The Schedule referred to in these Letters Patent and making part of the same.

To all whom it may concern:

Be it known that I, FREDERICK WHITEHOUSE, of Brooklyn, in the county of Kings, and State of New York, have invented a new and improved Design for Spoon; and I do hereby declare that the following is a full, clear, and exact description thereof, which will enable those skilled in the art to make and use the same, reference being had to the accompanying drawings, forming part of this specification.

This invention relates to a new and original design for a tablespoon; and

It consists of certain embellishments on the front and back of the spoon.

In the accompanying sheet of drawings—

Figure 1 is a front or face view of a tablespoon, and

Figure 2, a back view of the same, showing my design.

Similar letters of reference indicate corresponding parts.

The contour of the bowl A is of the usual form, as is also that of the main portion, B, of the handle.

The flattened end, C, of the handle is rather more pointed than usual, although it is not an uncommon shape.

On the front side of the part B of the handle, at each side, there is a raised bead, a, the lower ends of which beads come inward, or toward each other, in semicircular form, a raised ornament, b, being directly over the curved ends. (See fig. 1.)

Around the front or face side of the flattened portion C of the handle, there is first, near the edge, a fine bead, e, like a, then a coarse bead, d, and a fine bead,

e, at the inner edge of d, the upper part of e not being continuous, but disconnected, and the ends terminating with a semicircle, with a small raised figure, f, between, above which there is a raised ornament, g, and a smaller one, h, below.

The lower parts of the three beads c d e connect with scrolls i i, each of which has a raised figure, j, within it, a raised figure, k, being between the scrolls, a small ornament, l, above it, and a larger one, m, below, which extends downward upon the portion B of the handle.

The back of the spoon is ornamented at its upper part precisely like the front, but the ornament at the lower part is different.

The lower part of the beads a is forked, one branch, n, terminating at the junction of the part B of the handle with the bowl A, while the other branches, o, extend downward on the rear of the bowl, cross each other, and form each a scroll, p, with a raised figure, r, within them, a raised ornament, s, being below the scrolls.

I claim as new, and desire to secure by Letters Patent—

A design for a tablespoon, substantially as herein shown and described.

The above specification of my invention signed by me, this 12th of August, 1868.

FRED'K WHITEHOUSE.
